UNITED STATES PATENT OFFICE.

RUSSELL T. KINGSFORD, OF WYNCOTE, PENNSYLVANIA, ASSIGNOR TO ATWATER KENT MANUFACTURING COMPANY, OF PHILADELPHIA, PENNSYLVANIA, A CORPORATION OF PENNSYLVANIA.

DESIGN FOR A GRILLE FRONT FOR RADIO LOUD SPEAKERS.

Application filed June 3, 1927. Serial No. 22,314. Term of patent 7 years.

To all whom it may concern:

Be it known that I, RUSSELL T. KINGSFORD, a citizen of the United States, residing at Wyncote, county of Montgomery, and State of Pennsylvania, have invented a new, original, and ornamental Design for a Grille Front for Radio Loud Speakers, of which the following is a specification, reference being had to the accompanying drawing, forming part hereof.

The drawing is a front elevational view of a grille front for radio loud speakers, showing my design.

I claim:

The ornamental design for a grille front for radio loud speakers, as shown.

RUSSELL T. KINGSFORD.
